UNITED STATES PATENT OFFICE.

MICHAEL F. MAHONEY, OF NEW HAVEN, CONNECTICUT, ASSIGNOR OF ONE-HALF TO JOHN W. DOYLE, OF EAST HAVEN, CONNECTICUT.

SHEET-FEEDING MECHANISM.

No. 873,322.

Specification of Letters Patent.

Patented Dec. 10, 1907.

Application filed August 31, 1907. Serial No. 390,914.

To all whom it may concern:

Be it known that I, MICHAEL F. MAHONEY, a citizen of the United States, residing at New Haven, county of New Haven, State of Connecticut, have invented a new and useful Sheet-Feeding Mechanism, of which the following is a specification.

This invention has for its object to provide sheet feeding mechanism adapted for use in connection with presses generally, as for example printing presses, and especially applicable to presses for cutting and creasing paper boxes.

It is, of course, well understood that in the manufacture of paper boxes the speed of the machine is necessarily limited to the speed at which the operator can feed the sheets. It is furthermore well understood that in the manufacture of paper boxes the very best operators spoil a high percentage of the sheets owing to the fact that it is impossible when working at a high speed to insure the accurate feeding of every sheet. It is furthermore well understood that in feeding the sheets to paper box machines, the operator is in constant danger of having his hand caught between the platen and the bed, and being seriously injured thereby.

My present invention enables the manufacturer to dispense entirely with skilled labor in running the presses, as hand feeding in the ordinary sense is entirely done away with and it is only necessary to provide unskilled labor to supply sheets to the feeding mechanism, the feeding by means of my present invention being very much more rapid than has heretofore been possible, thereby greatly increasing the product of the presses and at a greatly reduced cost for labor, and still further reducing the cost of production by entirely eliminating the loss from spoiled sheets, and lastly, but by no means least important, my present invention entirely eliminates the liability of injury to the operator.

With these and other objects in view I have devised the simple and novel sheet feeding mechanism which I will now describe, referring to the accompanying drawings forming a part of this specification and using reference characters to indicate the several parts:

Figure 1 is a side elevation of one end of a press, for example a press for use in cutting and creasing paper boxes with my novel feeding mechanism applied thereto; Fig. 2 a

plan view corresponding therewith; Fig. 3 an enlarged end elevation of the gripping mechanism, the gripper shaft being in section on the line 5—5 in Fig. 2 looking in the direction of the arrow and the position of the gripping mechanism relatively to the table being indicated by the line 3—4 in Fig. 2; one pair of grippers being in the open position and about to grip a sheet; Fig. 4 a similar view when the gripper has gripped a sheet an instant later; Fig. 5 a similar view, the gripper shaft being in section and in the position indicated by the line 5—5 in Fig. 2; Fig. 6 an enlarged detail elevation, the gripper shaft being in section on the line 6—6 in Fig. 2 looking in the direction of the arrows; Fig. 7 an elevation of the same mechanism from a point of view opposite to that in Fig. 6, the position of the parts corresponding with Fig. 5 and the full line position in Fig. 1; and Fig. 8 is a detail plan view corresponding with Fig. 7.

10 denotes the bed of a press, 11 the driving gear, 12 the platen which is provided with side plates 13, and 14 a connecting rod pivoted to the driving gear and to one of the side plates of the platen. Each of the side plates of the platen is provided with a roller 15 (see dotted lines, Figs. 1 and 2), which travels on the edge of a plate 16, the said plates being on opposite sides of the press as clearly shown in Fig. 2. The above parts are those of an ordinary swinging platen press and their special construction or configuration is unimportant so far as the present invention is concerned. 17 denotes rods extending from the ends of the outer edge of the platen. These rods are shown as provided with attaching plates 18 by means of which they are rigidly secured to the platen.

19 denotes carriers adapted to reciprocate on the rods and 20 coil springs on the rod which bear against the ends of the carriers and against collars 21 rigidly secured to the outer ends of the rods. At the inner ends of the carriers and extending outward therefrom are studs 22 which carry grooved rollers 23 adapted to travel on cam tracks 24. The inner end of each cam track is rigidly secured to the frame of the press as at 25, the outer ends of the cam tracks being shown as extending downward and rigidly secured to the floor, which supports the press, as at 26. At the outer ends of the carriers and extending downward therefrom are hubs 27 in which the gripper shaft 28 is journaled. At the 110

- mid-length of the gripper shaft and rigidly secured thereto is a plate 29 which is provided with three arms indicated by 30, each of which carries an independent gripper. 5 Each gripper comprises two or more pairs of gripping fingers (two pairs being shown in the drawings) and gripper strips to which the gripping fingers are adjustably secured and which are hinged to each other, one of said 10 gripper strips being rigidly secured to one of the arms 30 and the other gripper strip being rigidly secured to a gripper arm which is pivoted to said arm 30.
- 31 denotes the gripping fingers, 32 the 15 fixed gripper strips, 33 the movable gripper strips and 34 the gripper arms. The gripping fingers are shown as provided with slots 35 and are secured to the gripper strips by means of screws 36 passing through said slots. 20 The outer end of each arm 30 is provided with a recess 37, and the fixed gripper strip 32 is rigidly secured in the face of this recess. The corresponding movable gripper strip 33 faces the fixed gripper strip and is rigidly secured to a gripper arm 34. 25
- 39 denotes hinges by which the fixed and movable gripper strips are connected to each other.
- The inner end of each gripper arm 34 is 30 provided with a segment gear 40 which meshes with a corresponding segment gear 41 on an arm 42 carried by a rock shaft 43. There are three of these rock shafts 43 corresponding 35 with the three grippers. The inner ends of these rock shafts are mounted to oscillate in plate 29 and the outer ends are mounted to oscillate in a collar 44 on gripper shaft 28. At the outer end of each rock shaft 43 is a crank arm 45, the outer end of which is preferably 40 provided with a roller 46, said rollers being adapted to engage a cam 47 which is rigidly secured to any suitable fixture, and also a cam 75 presently to be described. In the present instance, I have shown cam 47 as 45 rigidly secured to and projecting from one of the cam tracks 24 (see the cam track at top of sheet in Fig. 2).
- 76 denotes springs secured to arms 30 and bearing upon the gripper strips, the action of 50 which is to retain the gripping fingers in the gripping position.
- 48 denotes angle plates near the opposite ends of gripper shaft 28, and 49 springs rigidly secured to carriers 19 and extending into 55 position to be engaged by either of the sides of the angle plates, said angle plates being provided with three sides and the function of said plates and the corresponding springs being to retain the gripper shaft and grippers in 60 position after each actuation of the shaft which will presently be fully explained.
- At the end of gripper shaft 28 opposite to cam 47 is a ratchet wheel 50 rigidly secured to the shaft. This ratchet wheel is engaged 65 by a spring-actuated pawl 51 carried by a

housing 52 on an arm 53 which is mounted to oscillate on the gripper shaft.

54 denotes an operating arm which is pivoted to the outer end of arm 53 and is provided at its opposite end with a slot 55 through which a screw stud 56 passes, said stud engaging the collar 21 at the outer end of the rod 17 on that side of the device and said collar being provided with a flattened face corresponding with the face of the operating arm as indicated at 57. It will be noted that operating arm 54 and crank arms 45 on rods 43 are placed on opposite sides of the device for convenience in arrangement. 75

Above frame 10 of the press is secured a 80 frame 58 which supports an adjustable table 59 which is supplied with sheets by the operator, a sheet on the table in the act of being gripped by the fingers being indicated by 60 (see Figs. 1, 3 and 4). 85

In order to provide for feeding various sizes of sheets, I make the table adjustable both longitudinally and vertically. The longitudinal adjustment of the table is effected by means of slots 61 near the edges of the 90 table through which screws 62 pass and engage frame 58. In order to provide the necessary vertical adjustment for the forward edge of the table, I divide the table transversely into two parts which are hinged together as at 63. The forward edge of the table may be raised to any required adjustment by means of screws 64 which pass through frame 58 and engage the underside of the table. If required to raise the table, the set screws are turned inward and after the table is raised to the required adjustment the screws are locked in position by set nuts 65. For the convenience of the operator, I provide one or more side guides 66 upon one 105 side of the table. The side guide shown is provided with a longitudinal slot 77 and is secured in place by a set screw 78 passing through the slot. At the forward edge of the table and journaled in bearings 67 secured to the underside of the table is a rock shaft 68 having extending therefrom two or more stop pins 69 which project upward slightly above the top of the table and normally form stops for engagement by the forward edge of the 110 sheet, as clearly shown in Fig. 3.

70 denotes an arm extending from the rock shaft and 71 a rod connecting said arm to a lever 72 which is pivoted to a hub 73 extending from a bracket 74 which projects outward 120 from frame 58.

The parts may be so constructed as to be self-retaining in their normal position by gravity, as, for example, the rear end of lever 72 may be provided with a weight as indicated by 79 in Fig. 3. 125

At the outer end of bracket 74 is a cam 75 which is adapted to be engaged by one of the crank arms 45 to open the corresponding grippers and by the rear end of lever 72 to 130

5 oscillate rock shaft 68 and swing the stop pins out of the way of the sheet, as will be more fully explained. The forward end of lever 72 is in practice provided with a slot or a plurality of holes as shown to provide an 10 adjustable connection of rod 71 to said lever to correspond with different adjustments of the table.

10 The operation is as follows: It will be understood that the grippers are normally held closed by springs 76. Fig. 3 shows a position of the parts just before a gripper has reached the gripping position, which is at the extreme of the movement of the gripper shaft toward 15 the table, and Fig. 4 shows a position of the parts just after a sheet has been gripped and the gripper shaft has commenced to travel backward. As a gripper approaches the position shown in Fig. 3, its crank arm 45 (shown as provided with a roller 46) will engage cam 75 and pass under said cam, the effect of which is to oscillate the rock shaft 43 and move gripping fingers 31 to the open position as in Fig. 3, against the power of spring 20 76. It has already been stated that the sheet to be operated upon is placed in engagement with the stop pins 69 on rock shaft 68. When the grippers reach the extreme of their forward movement, an instant after the 25 position shown in Fig. 3 and an instant before the position shown in Fig. 4, the end of the crank arm will pass forward and out from under cam 75. The instant this movement takes place, spring 76 will close the gripping 30 fingers upon the edge of the sheet, the effect of which will be to oscillate segment gears 40 and 41 and throw crank arm 45 upward, bringing said crank arm into engagement with lever 72, tilting said lever, oscillating 35 rock shaft 68 and swinging the stop pins out of the way of the sheet, as in Fig. 4. The backward movement of the gripper draws the sheet off from the table. The instant the rear end of lever 72 passes off from 40 cam 75 in the backward movement, the lever will drop by gravity and will return the rock shaft and stop pins to their normal position ready to be engaged by the next sheet. Turning now to Fig. 1, the dotted position of 45 the grippers corresponds substantially with Fig. 3. While the platen is in the dotted position in Fig. 1, an operation is being performed upon the sheet last previously removed from the table. The nature of this 50 operation, as already stated, is wholly unimportant so far as the present invention is concerned. The rotary movement of the driving gear and the oscillatory movement of the platen is continuous. As the grippers travel 55 backward, the grooved rollers 23 on carriers 19 travel backward on the cam tracks, the effect of which is, from the dotted position of the grippers shown in Fig. 1 until the rollers have reached the high portions of the cam 60 tracks, indicated by 80, to force carriers 19

outward on rods 17 against the power of springs 20. The effect of this movement is, through the action of operating arm 54, arm 53, pawl 51 and ratchet wheel 50 on the gripper shaft which is engaged by said pawl, to 70 impart a third of a rotation to the gripper shaft and grippers against the power of springs 49 which engage angle plates 48 on the gripper shaft. As soon as this movement of the gripper shafts and grippers is 75 completed, which is at the instant rollers 23 on the carriers have reached the high portions of the cam tracks, the gripper shaft and grippers will be again locked in position through the engagement of springs 49 with 80 the next faces of angle plates 48 to come into the locking position, as clearly shown in Figs. 6 and 7. The position of arm 53 and operating arm 54 in Fig. 6 corresponds with the dotted position of the grippers in Fig. 1, 85 that is, at the commencement of the turning movement.

Fig. 7 shows the position of the parts at the end of the turning movement of the gripper shaft, that is, at the instant rollers 23 are 90 at the high portion of the cam track. At the commencement of the movement, springs 20 on rods 17 will be extended as in Fig. 6 and screw studs 56 will be at the outer ends of slots 55 in the operating arms. At the end 95 of the turning movement, screw studs 56 will be at the inner ends of the slots in the operating arms, carriers 19 will be at their farthest outward position on rods 17 and springs 20 will be compressed between the 100 ends of the carriers and collars 21 at the outer ends of the rods. While rollers 23 and carriers 19 are passing backward from the high portions of the cam tracks, which for convenience I have indicated by 80, to the 105 position shown in Fig. 1, there will be no change in the relative position of the carriers, gripper shaft and grippers. The effect of the turning movement of the gripper shafts and grippers will be to draw the sheet that was 110 being operated upon when the platen was in the dotted position in Fig. 1 entirely off from the platen and to draw the sheet which has just been gripped, as already described, backward partially off from the platen. This 115 drawing of the gripped sheet partially off from the platen before it has been operated upon is simply an incident of the construction of the device and has no function whatever. When the gripper shaft and grippers have reached the extreme of their backward 120 movement, the grippers and the platen will be in the full line position in Fig. 1. As the carriers and grippers approach this position, the crank arm 45 corresponding with the 125 gripping fingers holding the sheet that has just been operated upon and drawn off from the platen will ride up on cam 47 (see Fig. 5, in connection with Figs. 1 and 2), the effect of which will be to oscillate the crank 130

shaft and the corresponding rock shaft 43 and to open that gripper through the action of segment gears 40 and 41, allowing the sheet that has just been operated upon to 5 drop out, the open position of the gripper being clearly shown in Figs. 1 and 5. In Fig. 1 the gripper that will next grip a sheet is indicated by *a*, the gripper which is holding a sheet previous to its being operated upon is 10 indicated by *b* and the gripper which has just released a sheet is indicated by *c*. An instant after the release of a sheet the gripper shaft and grippers commence to move forward from the full line position in Fig. 1 15 toward the dotted position in Fig. 1. While the grippers are moving from the full line position in Fig. 1 to the high portions of the cam tracks, there will be no change in the relative position of the grippers except that 20 the crank arm 45 of the gripper that has just released a sheet, as in Fig. 5 and gripper *c* in Fig. 1, will pass backward off from cam 47 and the corresponding spring 76 will carry the movable gripping fingers to the closed 25 position. When the grippers in their forward movement reach high portions 80 of the cam tracks, carriers 19, operating arm 54 and arm 53 will still be in the position shown in Fig. 7. As the cam shaft and grippers 30 pass from high portions 80 of the cam track toward the dotted position in Fig. 1, the operating arm, arm 53 and the carriers will commence to slide inward on rods 17 from the position shown in Fig. 7 toward the position shown in Fig. 6, the pawl during this 35 movement passing backward over the teeth of ratchet wheel 50. When the parts have reached the position shown in Fig. 6, the pawl will be in engagement with the ratchet 40 wheel ready to impart another one-third rotation to the gripper shaft and grippers after the next sheet has been seized by a pair of gripping fingers and while the gripper shaft and carriers are moving from the dotted position in Fig. 1 toward high portion 80 of the 45 cam tracks. The movements just described are continuously repeated during the operation of the machine, the mechanism easily handling two thousand or more sheets per 50 hour, that is taking the sheets singly from the table, holding them while they are being operated upon and then releasing them, the machine being operated without skilled labor, without danger to the operator and 55 without injury to the sheets operated upon and the mechanism handling moreover a far greater number of sheets than it is possible to handle by any means heretofore known in the art. In use, the sheets to be operated 60 upon are centered relatively to the center of the platen. For larger sheets, the table is moved forward and the gripping fingers are set backward on the gripper strips and for smaller sheets the table is set farther back, 65 that is away from the grippers, the forward

end of the table is preferably tilted more or less by means of the set screws and the gripping fingers are moved forward on the gripper strips.

Having thus described my invention, I claim:

1. The combination with a swinging platen having rods extending therefrom, of carriers adapted to reciprocate on said rods, a rotating gripper shaft journaled in said carriers, 75 grippers carried thereby and mechanism for opening and closing the grippers.

2. The combination with a swinging platen having rods extending therefrom, of carriers adapted to reciprocate on said rods, rollers 80 upon the carriers, cam tracks upon which the rollers travel, a gripper shaft journaled in the carriers, grippers carried by said shaft and mechanism for opening and closing the grippers.

3. In a press, the combination with a bed, a swinging platen having rods extending therefrom and cam tracks, of carriers adapted to reciprocate on the rods, grooved rollers 85 on the carriers engaging the cam tracks, and a gripper shaft journaled in the carriers.

4. The combination with a swinging platen having rods extending therefrom and provided with collars at their outer ends, of carriers on said rods, rollers on the carriers, a 95 cam track engaged by the rollers and springs intermediate the carriers and the collars, said cam tracks and springs acting to reciprocate the carriers on the rods when the platen is operated.

5. The combination with a swinging platen having rods extending therefrom and provided with collars at their outer ends, of carriers on said rods, rollers on the carriers, a cam track engaged by said rollers, springs 105 intermediate the carriers and the collars for the purpose set forth, and a gripper shaft journaled in the carriers.

6. The combination with a swinging platen having rods extending therefrom, of carriers 110 adapted to reciprocate on said rods, a rotating gripper shaft journaled in said carriers, and grippers carried by said shaft, each gripper comprising a plurality of gripping fingers, gripper strips to which the fingers are adjustably secured and means for opening and closing said grippers.

7. The combination with a swinging platen having rods extending therefrom, of carriers adapted to reciprocate on said rods, a rotating gripper shaft journaled in said carriers, a three armed plate carried by the gripper shaft, grippers carried by said plate and mechanism for opening and closing the grippers.

8. The combination with reciprocating carriers, a gripper shaft journaled in said carriers and a three-armed plate carried by said shaft, of gripper strips secured to said arms, gripper arms pivoted to said arms,

85

100

115

125

120

130

gripper strips secured to the gripper arms, gripping fingers carried by the gripper strips and means for oscillating the gripper arms to open and close the gripping fingers.

5 9. The combination with reciprocating carriers, a gripper shaft journaled in said carriers and a plate carried by said shaft and provided with arms 30 having recesses 37, of gripper arms pivoted to arms 30, gripper strips secured in said recesses and gripper strips secured to the gripper arms and means for oscillating the gripper arms.

10 10. The combination with reciprocating carriers, a rotating gripper shaft journaled in said carriers and a plate carried by said shaft and provided with arms 30, of a pair of gripper strips supported by each of said arms 30, and adjustable gripping fingers carried by the gripper strips.

15 11. The combination with reciprocating carriers, a rotating gripper shaft journaled in said carriers and a plate carried by said shaft and provided with arms 30, of grippers comprising a pair of gripper strips supported by each of said arms and gripping fingers mounted on said strips, and means for operating said grippers.

20 12. The combination with reciprocating carriers, a gripper shaft journaled in said carriers and a plate carried by said shaft, and provided with arms 30, of gripper arms pivoted to arms 30 and provided with gears, arms 42 having segment gears meshing with said gears on said gripper arms, rock shafts carried by the gripper shaft by which arms 42 are carried, crank arms on said rock shafts, and a cam adapted to be engaged by the said crank arms to oscillate the gripper arms.

25 13. The combination with reciprocating carriers, a gripper shaft journaled in said carriers and a plate having arms 30 and a collar carried by said shaft, of rock shafts journaled in said plate and said collar, crank arms and arms 42 carried by said rock shafts, gripper arms pivoted to arms 30, intermeshing gears on the gripper arms and arms 42 and a cam adapted to be engaged by the crank arms to oscillate the gripper arms.

30 14. The combination with reciprocating carriers, a gripper shaft journaled in said carriers and a plate having arms 30 carried by said shaft, of gripper arms pivoted to arms 30, rock shafts carried by the gripper shaft, connections intermediate the rock shafts and the gripper arms, and means for oscillating the rock shafts to open the gripper arms.

35 15. The combination with reciprocating carriers, a gripper shaft journaled in said carriers and a plate having arms 30 carried by said shaft, of gripper arms pivoted to arms 30, rock shafts carried by the gripper shaft, connections intermediate the rock shafts and the gripper arms, means for oscillating the rock shafts to open the gripper arms and

40 springs for retaining the gripper arms in the closed position.

16. The combination with reciprocating carriers, a gripper shaft journaled in said carriers and a plate having arms 30 carried by said shaft, of a pair of grippers supported by each of said arms 30, each of said pairs of grippers including a gripper having a gear, arms 42 having gears corresponding with the gears on said gripper arms, rock shafts by 70 which arms 42 are carried, springs for retaining the gripper arms in the closed position and means for oscillating the rock shaft to open the gripper arms against the power of the springs.

80 17. The combination with reciprocating carriers, a gripper shaft journaled in said carriers and a plate having arms 30 carried by said shaft, of gripper arms pivoted to arms 30, rock shafts carried by the gripper shaft 85 and having arms 42 and crank arms, corresponding segment gears on the gripper arms and arms 42, springs for retaining the gripper arms in the closed position and a cam adapted to be engaged by the crank arms to 90 oscillate the gripper arms against the power of the springs.

18. The combination with reciprocating carriers, a gripper shaft journaled in said carriers and a plate having arms 30 carried by said shaft, of gripper arms pivoted to arms 30, and gripper strips carried by the gripper arms and arms 30 and hinged to each other.

95 19. The combination with reciprocating carriers, a gripper shaft journaled in said carriers and a plate having arms 30 carried by said shaft, of gripper arms pivoted to arms 30, and gripper strips carried by the gripper arms and arms 30 and hinged to each other, 100 springs for retaining the gripper arms in the closing position and means for oscillating the gripper arms against the power of the springs.

105 20. The combination with reciprocating carriers, a gripper shaft journaled in said carriers and a plate having arms 30 carried by said shaft, of gripper arms pivoted to arms 30, and gripper strips carried by the gripper arms and arms 30 and hinged to each other, 110 adjustable gripping fingers carried by the gripper strips and means for opening and closing the gripper arms.

115 21. The combination with the platen, of reciprocating carriers connected with said platen to swing therewith, a gripper shaft journaled in said carriers, a plate on said shaft, grippers carried by said plate, and means for opening and closing said grippers.

120 22. The combination with the platen, of reciprocating carriers connected with said platen to swing therewith, a gripper shaft journaled in said carriers, a plate on said shaft, grippers carried by said plate, means for opening and closing the grippers, and means for imparting rotary movement in a continuous direction to the gripper shaft.

23. The combination with reciprocating carriers, a gripper shaft journaled in said carriers and a gripper-carrying plate on said shaft, of means for opening and closing the grippers, means for imparting an intermittent rotary movement in a continuous direction to the gripper shaft, and means for retaining the gripper shaft in position after each actuation. 5
- 10 24. The combination with a swinging platen having rods extending therefrom and provided with collars at their outer ends, reciprocating carriers on said rods, a gripper shaft journaled in said carriers, and a gripper carrying plate and ratchet wheel on said shaft, of a housing mounted to oscillate on the gripper shaft, a spring actuated pawl carried by said housing and engaging the ratchet wheel, an operating arm pivoted to the housing and having at its opposite end a slot, and a stud passing through said slot and fixed to one of the collars. 15
- 15 25. The combination with a swinging platen, rods extending therefrom and collars on said rods, of carriers on the rods, rollers on the carriers, cam tracks engaged by said rollers, a gripper shaft journaled in the carriers and carrying a ratchet, an arm mounted to oscillate on the gripper shaft, a spring-actuated pawl carried by said arm and engaging the ratchet and an operating arm pivoted to the pawl carrying arm and having a slot and stud connection with the collar on one of the rods, whereby the carriers are 20 caused to reciprocate on the rods and rotary movement is imparted to the gripper shaft. 30
- 20 26. The combination with a swinging platen, rods extending therefrom and carriers on the rods, of cam tracks on which the carriers travel, a gripper shaft journaled in the carriers and pawl and ratchet mechanism for imparting rotary movement to the gripper shaft. 40
- 25 27. The combination with a swinging platen, rods extending therefrom and carriers on the rods, of cam tracks on which the carriers travel, a gripper shaft journaled in the carriers, an arm mounted to oscillate on the gripper shaft, an operating arm pivoted to said arm and having a slot and stud connection with one of the rods and pawl and ratchet connections, whereby movement of the carriers in one direction will impart rotary movement to the gripper shaft. 50
- 50 28. The combination with a swinging platen, rods extending therefrom and collars and carriers on the rods, of cam tracks on which the carriers travel, springs intermediate the carriers and collars, a gripper shaft journaled in the carriers and connections intermediate the gripper shaft and one of the rods whereby movement of the carriers in one direction will impart rotary movement to the gripper shaft. 60
- 55 29. The combination with a swinging platen, rods extending therefrom and carriers on the rods, of cam tracks on which the carriers travel, a gripper shaft journaled in the carriers, an angle plate on the gripper shaft, connections intermediate the gripper shaft and one of the rods, for the purpose set forth, and a spring engaging the angle plate to retain the gripper shaft after each actuation. 65
- 65 30. The combination with a swinging platen, rods extending therefrom and having collars at their ends and carriers on the rods, of cam tracks on which the carriers travel, springs intermediate the carriers and collars, a gripper shaft journaled on the carriers and having a ratchet wheel, an arm mounted to oscillate on the gripper shaft, a pawl on said arm engaging the ratchet and an operating arm pivoted to said arm and having a stud and slot connection with the collar on the corresponding rod. 70
- 70 31. The combination with a swinging platen, rods extending therefrom, carriers on the rods and a rotating gripper shaft journaled in the carriers, of grippers carried by said shaft, mechanism for opening and closing the grippers, and a table from which sheets are taken by the grippers. 80
- 80 32. The combination with a swinging platen, a gripper shaft carrying grippers, mechanism for imparting rotary movement to the gripper shaft and mechanism for opening and closing the grippers, of a table from which sheets are taken by the grippers, a rock shaft at the forward edge of the table 100 having stop pins for engagement by the sheets, and mechanism for oscillating the rock shaft to swing the stop pins away from the sheets. 95
- 95 33. The combination with a swinging platen, a gripper shaft carrying grippers, mechanism for imparting rotary movement to the gripper shaft and mechanism for opening and closing the grippers, of a table from which sheets are taken by the grippers, a rock shaft at the forward edge of the table 110 having stop pins for engagement by the sheets, and an arm 70, a lever 72, a rod connecting said lever with arm 70 and means for oscillating said lever to swing the stop pins 115 away from the sheets. 105
- 105 34. The combination with a swinging platen, a gripper shaft carrying grippers, mechanism for imparting rotary movement to the gripper shaft and mechanism for opening and closing the grippers, of a table from which sheets are taken by the grippers, a rock shaft at the forward edge of the table 120 having stop pins for engagement by the sheets, and an arm 70, a lever having a weight at its rear end, a rod connecting said lever with arm 70 and means for oscillating said lever to swing the stop pins away from 125

the sheet to be operated upon, the weight on the lever acting to return the stop pin to position for engagement by the next sheet.

35. The combination with a swinging platen, a gripper shaft, grippers carried thereby, mechanism for imparting rotary movement to the gripper shaft, rock shafts carried by the gripper shaft and provided with crank arms and operating connections between the rock shafts and the grippers, of a table for sheets, a cam 75 which is engaged by each crank arm to open the corresponding gripper when in position to take a sheet and a cam 47 which is engaged by each crank arm when the corresponding gripper is in position to release a sheet.

36. The combination with a swinging platen, a gripper shaft, grippers carried thereby, mechanism for imparting rotary movement to the gripper shaft, rock shafts carried by the gripper shaft and provided with crank arms and operating connections between the rock shafts and the grippers, of a table for sheets, a rock shaft at the forward edge of the table having stop pins for engagement by the sheets and an arm 70, a weighted lever, a rod connecting said lever with arm 70 and cams 47 and 75 which are engaged by the crank arms, substantially as described for the purpose specified.

37. The combination with a swinging platen, reciprocating carriers, a gripper shaft journaled in the carriers, and grippers carried by said shaft, of rock shafts carried by the gripper shaft and provided with crank arms, operating connections between the crank arms and the grippers, springs for closing the grippers, means for imparting rotary movement to the gripper shaft and cams 75 and 47 which are adapted to be engaged by the crank arms to open the grippers to receive and to release a sheet.

38. The combination with a swinging platen, reciprocating carriers, a gripper shaft journaled in the carriers, and grippers carried by said shaft, of rock shafts carried by the gripper shaft and provided with crank arms, operating connections between the crank arms and the grippers, springs for closing the grippers, means for imparting rotary movement to the gripper shaft, means for retaining the gripper shaft after each actuation, and cams engaged by the crank arms to open the grippers at predetermined times.

39. The combination with a swinging platen, reciprocating carriers, a gripper shaft journaled in the carriers, and grippers carried by said shaft, of rock shafts carried by the gripper shaft and provided with crank arms, operating connections between the crank arms and the grippers, springs for closing the grippers, ratchet mechanism for imparting rotary movement to the gripper shaft, means for retaining the gripper shaft after each actuation and cams engaged by

the crank arms to open the grippers at predetermined times.

40. The combination with a swinging platen, reciprocating carriers, a gripper shaft journaled in the carriers and grippers and an angle plate carried by said shaft, of rock shafts also carried by the gripper shaft and provided with crank arms, operating connections between the crank arms and the grippers, springs for closing the grippers, means for imparting rotary movement to the gripper shaft, a spring engaging the angle plate to retain the gripper shaft after each actuation and cams engaged by the crank arms to open the grippers at predetermined times.

41. The combination with a swinging platen, reciprocating carriers, a gripper shaft journaled in the carriers and grippers carried by said shaft, of means for imparting rotary movement in a continuous direction to the gripper shaft and means for opening and closing the grippers at predetermined times.

42. The combination with a swinging platen, reciprocating carriers, a gripper shaft journaled in the carriers and grippers carried by said shaft, of means for imparting rotary movement in a continuous direction to the gripper shaft, means for opening and closing the grippers at predetermined times, a table for sheets, a rock shaft at the forward edge of said table which is provided with stop pins and means for oscillating said rock shaft and pins when a sheet is taken by the grippers.

43. The combination with a swinging platen, reciprocating carriers, a gripper shaft journaled in the carriers and grippers carried by said shaft, of means for imparting rotary movement in a continuous direction to the gripper shaft, a table, means for adjusting said table, for the purpose set forth, and means for opening and closing the grippers at predetermined times.

44. The combination with a swinging platen having rods extending therefrom, reciprocating carriers movably mounted on said rods, a rotating gripper shaft journaled in the carriers and three sets of gripping fingers carried by said shaft, of a table for sheets, means for imparting rotary movement to the gripper shaft, and means for opening and closing the gripping fingers at predetermined times, whereby in use a sheet is held by one set of gripping fingers while being operated upon, a sheet is being taken by another set of fingers and the sheet previously operated upon is being released by the other set of fingers.

45. The combination with a swinging platen having rods extending therefrom, reciprocating carriers movably mounted on said rods, a rotating shaft journaled in said carriers and grippers carried by said shaft, of a table for sheets divided transversely and hinged, screws for adjusting the forward edge of the table, means for imparting rotary

movement to the gripper shaft and means for opening and closing the grippers to take and release the sheets.

46. The combination with a swinging platen having rods extending therefrom, reciprocating carriers movably mounted on said rods, a rotating shaft journaled in said carriers and grippers carried by said shaft, of a table for sheets divided transversely and hinged, screws for adjusting the forward edge of the table, a rock-shaft at the forward edge of the table provided with stop pins, means for imparting rotary movement to the gripper shaft, means for opening and closing the grippers to take and release the sheets, and means for oscillating the rock shaft and stop pins when a sheet is taken by a gripper.

47. The combination with a swinging platen, reciprocating carriers, a gripper shaft journaled in said carriers and grippers carried by said shaft, of rock shafts 43 carried by the gripper shaft and provided with crank arms, operating connections intermediate

the rock shafts and the grippers, springs 76 for retaining the grippers closed, means for imparting rotary movement to the gripper shaft, a table for sheets, a rock shaft 68 at the forward edge of said table and provided with stop pins and an arm, a weighted lever, a rod connecting said lever with said arms, and a cam 75 adapted to be engaged by each crank arm to open the corresponding gripper when in position to take a sheet and swing the stop pins away from the sheet, spring 76 closing the gripper as soon as the crank arm has passed the cam and causing the crank arm to engage the lever which in turn oscillates rock shaft 68 and returns the stop pins to their normal position.

In testimony whereof I affix my signature, in presence of two witnesses.

MICHAEL F. MAHONEY. [L. s.]
